UNITED STATES PATENT OFFICE.

OLOF OHLSON, OF WEST NEWTON, MASSACHUSETTS, ASSIGNOR TO WALTHAM WATCH COMPANY, OF WALTHAM, MASSACHUSETTS, A CORPORATION OF MASSACHUSETTS.

CLOCK-MOUNTING.

1,145,698.

Specification of Letters Patent.

Patented July 6, 1915.

Application filed September 18, 1913. Serial No. 790,434.

To all whom it may concern:

Be it known that I, OLOF OHLSON, a citizen of the United States, and resident of West Newton, in the county of Middlesex and State of Massachusetts, have invented certain new and useful Improvements in Clock-Mountings, of which the following is a specification.

The present invention relates to a mounting or support for a timepiece designed to hold the timepiece against a substantially vertical wall with its face on an inclination, so that the same may be seen squarely from a view point above the time piece, and to support the timepiece thus in a manner which will permit its being wound and set by manipulation of the stem and will prevent theft of the timepiece.

The mounting or holder in which the present invention is embodied is particularly designed to secure a watch or clock upon the dashboard of a vehicle, the watch or clock being then somewhat below the eyes of the occupants of the vehicle, and to thus support the watch or clock so that the face is on a slant instead of vertical or parallel to the dashboard, and at the same time the watch or clock as a whole is as near as possible to the dashboard. For convenience in the following description, I refer to the timepiece in connection with which I employ my improved mounting as a watch simply, it being understood that this term is employed solely for convenience and brevity and without limiting significance.

The watch for which I have designed my improved holder is one in which the main spring is wound and the hands are set by a stem, and in which the dial and the figures on the dial are so placed that in order to be read easily the watch must be so placed that the stem is uppermost. This position of the watch and the inclination at which it must be held in order that the line of sight to the face will not be oblique to the face brings the stem close to the dashboard when in the upright position, in fact, so close that in this position it cannot be conveniently grasped and turned for winding and setting. This is because it is desirable that the watch should be as near as possible to the dashboard. It is also essential that the watch should be so mounted as to prevent theft without being so permanently held that it cannot be removed when necessary for re-

pairing. The requirements above outlined have, therefore, made it necessary to provide a form of mounting which will permit of the watch being turned about its axis to bring the stem at one side or even perhaps near the bottom, whereby it is brought far enough away from the dashboard to enable it to be very easily turned by twirling between one's thumb and finger for setting and winding, which mounting will at the same time secure the watch against removal by thieves whatever may be its position. The support or mounting which I am about to describe and claim contains the idea of means which I have devised for accomplishing the objects noted above.

In the drawings Figure 1 is a front elevation of a watch and its mounting, in which is contained my present invention. Fig. 2 is a side view of the same. Fig. 3 is a cross section of the mounting only showing the watch and the means for locking the same in the mounting in elevation. Fig. 4 is a rear elevation of the mounting. Fig. 5 is a plan view of the mounting with the watch removed. Fig. 6 is a rear elevation of the watch removed from the mounting. Fig. 7 is a perspective view of the watch. Fig. 8 is a detail view partly in elevation and partly in section of the watch and mounting interlocked. Figs. 9 and 10 are detail sectional views as seen from a plane immediately back of the forward wall of the mounting illustrating the mode of placing the watch therein and the manner in which the watch is retained in upright position. Fig. 11 is a cross section in the upper part of the mounting looking downwardly. Fig. 12 is a detail sectional view of the mounting and the retaining lock.

Like reference characters designate the same parts in all the figures.

1 represents a timepiece, which may be a watch or clock of any suitable character, preferably one having a lever escapement, so that it may continue to run in spite of being vibrated by a motor vehicle and being tipped as hereinafter described for winding and setting. It has a crown stem 2 for winding the spring and setting the hands. The manner in which it is desired to mount this timepiece is indicated best in Figs. 1 and 2, where 3 represents an upright wall, such as the dashboard of an automobile or any other wall. The watch is held at an inclina-

95

100

105

110

tion, as shown in Fig. 2, and at the same time as near as possible to the dashboard, with the result that the stem, which in the type of watch illustrated is at the top when the watch is so placed that its dial can be easily read, is so near the dashboard that it cannot be easily rolled between the thumb and finger. The mounting 4, which I have designed to hold the watch in this position, 10 is a bracket made conveniently of sheet metal having an ornamental finish and formed with an exterior which is continuous except for the opening in the front wall which receives the watch. Across the rear 15 of this bracket, which may be open, extends a bar 5, also conveniently of sheet metal, having flanges 6 at the top and bottom edges to stiffen it, and being secured at its ends to the side walls of the bracket. The 20 bar 5 is provided to receive the attaching bolts 7 which pass through it and through the dashboard and are equipped with holding nuts 8, such bolts being necessary to secure the mounting to the dashboard. The 25 rim or edge 9 of the bracket shell bears closely against the face of the dashboard and gives no access around it to the interior of the same.

In the front wall of the mounting or 30 bracket 4 is a circular opening, which is larger in diameter than the rear part 10 of the watch, but smaller than the case center 11. Hence this opening may receive the part 10 and obstruct the center 11, thereby 35 supporting the watch in the position shown in Fig. 3. At opposite points on the part 10 of the watch are ribs or wings 12, which project radially and are separated axially from the case center by a space sufficient to 40 admit the rim of the said opening in the front of the mounting. Such opening is cut away at opposite sides to form notches 13 of dimensions slightly greater, both radially and circumferentially, than the wings 45 12, provided to admit such wings and enable the back part of the watch to be inserted into the mounting when the watch is so placed as to cause the wings to register with these notches, this position being 50 shown in Fig. 10. After the watch has been thus placed and turned about its axis through a small angle to the position indicated by dotted lines in Fig. 9, it is securely held by the wings and case center embracing 55 between them the uncut rim of the opening in the mounting or bracket, as indicated in Fig. 8.

A retaining lock 14 is provided to limit 60 rotation of the watch and thereby prevent the watch from being so far turned after it has once been placed in the mounting as to permit its removal. Said lock is a tongue or finger which projects from the end of a lever 15 pivoted upon a pintle 16 which is 65 carried by a block 17 fastened to the upper-

most flange of the rear cross bar 5 of the mounting. A spring 18 is attached to the rear flange of the bar 5 and is engaged with the lock bar 15, the spring being so bent and set that it tends to throw the lock outwardly. 70 The lock is located in the bottom part of the case and lies in a cross cut or slot in a stud 19 fixed to the bottom wall of the mounting and provided to brace the lock and prevent it from being bent aside under 75 pressure. The position of the locking finger is such that it may be engaged by one end of either of the ribs 12 when the watch is turned in either direction, and the stud braces it so that it cannot yield when 80 pressed upon by either wing. It will be seen from Fig. 9 that the lock is within the lower notch of the front opening in the mounting, and from Fig. 3 it will be seen that the end of the lock is just within the 85 plane of such opening. When the watch is placed in the mounting, having first been brought into the position shown in Fig. 10, the lower wing upon passing through the notch 13 engages and pushes back the lock. 90 Then, when the watch is rotated far enough to carry the end of the wing past the lock, the latter is thrown out by spring 18 into the position shown in Fig. 3, where it remains as a stop to prevent the watch from 95 being turned far enough in either direction to bring its wings into registry with the notches. The dotted line representation of the watch in Fig. 9 shows how in the normal position the lock stops rotation of the 100 watch when the stem is uppermost and prevents it from being turned in the direction of the arrow far enough to permit removal. The turning movement in the opposite direction will be checked by engagement of 105 the upper wing with the lock before the watch can be turned far enough to uncover the wings. The fact that the lock is in the center of one of the notches and that the notches are only a slight amount longer than 110 the wings, makes it impossible to bring the watch into a position where the wings will 115 register with the slots. The total range of movement of the watch is the angular distance between the end of one wing and the beginning of the next which, as appears from Fig. 10, is somewhat more than 90°. The adjacent ends of the two wings thus constitute shoulders which limit the turning 120 movement of the watch by striking the stop or abutment which is constituted by the lock. One of the abutments is so located as to stop this motion when the stem is upright, and the other permits the watch to be turned so far that the stem is at the side, 125 as shown by dotted lines in Fig. 1, and is far enough removed from the dashboard to permit of being rotated without inconvenience.

The watch can be removed whenever 130

necessary by an authorized person having a key. It will be seen from Fig. 3 that the lock lever 15 crosses a tube 20 and lies in a transverse slot which partially divides such tube. The tube passes through one of the side walls of the mounting, and has a key slot 21 shown in Fig. 2 adapted to admit a key 22. The key is adapted to pass through the tube 20 until it crosses the lock lever 15, and then turn so that its edge or its wards bears against the lever, and is able to retract the latter and the lock, as shown by dotted lines in Fig. 1, until the lock is clear of the wings 12. Then the watch may be turned in either direction far enough to bring its wings opposite the notches 13. Preferably a certain amount of friction is provided between the mounting and the watch, such friction being provided for by bending or offsetting the edge of the opening in the mounting enough to make it rub against the center 11 and wings 12. The friction merely retains the watch in its upright position and prevents rattling.

In describing this invention as being used for an automobile watch mounting, I do not intend to be understood as limiting the invention in any manner. A mounting having the essential characteristics hereinbefore described and hereinafter claimed may be applied to many and various purposes and in many modifications wherever it is desirable to mount a timepiece against a surface of any character whatever, whether such surface is the dashboard of a vehicle or any other wall, or even a desk or other horizontal or inclined surface. In any case, the mounting securely retains the watch against removal except by the possessor of the key, while at the same time permitting as much movement of rotary displacement as is necessary for the purposes described.

What I claim and desire to secure by Letters Patent is:—

1. The combination of a watch having a setting and winding stem located at the upper part of the watch when the latter is in position for reading, a mounting adapted to be secured to a wall and having means for detachably securing the watch with provision for rotation about its axis, and a lock arranged to permit rotation of the watch through an angle sufficient to bring the stem from a position at the top to one at the side of said mounting, said lock being operative to prevent separation of the watch from the mounting when in either of said positions.

2. The combination of a watch and a mounting adapted to be secured upon a wall, said mounting having an opening of which the rim is inwardly turned and is arranged in a plane making an acute angle with the plane of the part which abuts against the wall, the watch having a case center adapted to overlie said rim and having a projecting

back of sufficiently small diameter to pass through the opening surrounded by the rim, and having also a winding stem adjacent to the upper side of the dial arranged when the watch is in normal position to lie close to the wall on which the bracket is mounted, said stem being in front of the plane of said rim, the back portion of the watch having a rigidly projecting wing and the said rim having a notch of dimensions sufficient to admit said wing, and locking means arranged in the mounting in position to permit a limited rotation of the watch upon the mounting and to prevent said watch from assuming a position in which the wing registers with the notch.

3. The combination of a watch having a case center, a wing in rear of said case center and separated therefrom by a narrow space, said wing being of limited length angularly about the axis of the watch, a mounting adapted to be secured upon a wall and having a front opening in a plane making an oblique angle with the plane of the mounting which abuts against the wall, said opening being of less diameter than the case center and having a notch adapted to admit said wing, the rim of said opening being inwardly turned and arranged to lie back of the case center and in the space between the case center and said wing when the watch is in its normal position, the watch having the stem adjacent to the top side of the dial, a lock adapted to be displaced for mounting and dismounting the watch, and normally crossing the path of said notch, whereby to prevent rotation of the watch into position for dismounting, and of permitting and limiting the amount of such rotation, said rim being shaped to bear against the case center and the said wing to provide for frictionally holding the watch against displacement from its normal position.

4. The combination with a timepiece having a projecting portion at its back of substantially circular outline and of less diameter than the widest part of the timepiece, and having also a winding stem at one side, a mount for the timepiece having an inwardly turned annular flange inclosing a circular opening of a diameter greater than that of said projection and less than the greatest width of the timepiece, said projection and said flange having complementary offsets arranged to be inter-engaged to prevent removal of the timepiece and adapted to come into registry when the timepiece is brought into a certain position, and a lock constructed and arranged to permit rotation of the timepiece and limit such rotation at a point short of the position where such portions come into registry.

5. The combination of a watch and a mounting therefor having an opening into which the rear part of the watch is adapted to ex-

tend, said mounting and watch having the contacting portions arranged to limit the extent to which the watch may enter such opening, the boundary of the opening having a rim in the plane of the watch, and an intermediate notch and the watch having a wing adapted to enter such notch and arranged to pass back of the rim of such opening beyond the end of such notch when the 10 watch is turned after being inserted in the opening, and a lock mounted displaceably between the ends of said notch intersecting the plane of said wing.

6. A watch mounting comprising a bracket 15 having a face provided with an opening and being otherwise inclosed, such opening being adapted to receive a projecting part of a watch or clock and having a portion of greater diameter than another portion of the opening, a lock located within said bracket and yieldingly held close to the plane of such opening at a point between the ends of the part thereof which has the greater diameter and within the outer boundary of such 25 part, said lock being displaceable away from the plane of such opening.

7. The combination of a watch and a bracket on which said watch is mounted, said bracket having an opening the rim of 30 which is turned inwardly and provided with oppositely located notches and the watch having a portion formed to pass through said opening and having wings adapted to pass through said notches and to be placed 35 back of said rim by rotation of the watch, and a lock contained within the bracket and yieldingly held toward one of said notches in position to be engaged and retracted by the wing which passes through such opening, and to be automatically projected when 40 the watch is so turned as to carry the end of

such wing past the lock whereby said lock occupies the space between the adjacent ends of two wings and is operative to prevent turning of the watch in either direction far enough to bring its wings into registry with such notches. 45

8. In combination a bracket or mounting having a circular opening in its front, a timepiece having a portion passing through 50 said opening and adapted to turn therewith, such portion of the timepiece having a wing or projection located back of the rim of such opening and preventing withdrawal therefrom and the opening having an enlargement 55 of a form similar to such projection and of a size sufficient to admit the latter when brought into registry therewith, and a lock contained within said bracket and located in position to engage said projection 60 so as to check rotation of the timepiece at a point short of the point at which its projection registers with said enlargement.

9. The combination of a watch mounting adapted to be secured upon a wall, a watch 65 having a winding stem, complementary means on the watch and mounting for holding the watch in a plane inclined to the wall at which the mounting is secured and its stem uppermost and close to such wall, said 70 means comprising interengaging elements on the watch and mounting arranged to permit rotation of the watch about its axis and constructed to cause frictional resistance 75 opposing such rotation, and a lock placed to limit positively the extent of such rotation.

In testimony whereof I have affixed my signature, in presence of two witnesses:

OLOF OHLSON.
